CLAIM

The ornamental design for a golf tee as shown and described.

DESCRIPTION

1.1 is a perspective view of the golf tee;

1.2 is a front plan view thereof;

1.3 is a back plan view thereof;

1.4 is a left side view thereof;

1.5 is a right side view thereof;

1.6 is a top plan view thereof;

1.7 is a bottom plan view thereof;

1.8 is a cross-section view thereof;

1.9 is an exploded view thereof;

1.10 is a front perspective view of the golf tee in an environment of use.

The broken lines shown in the drawings illustrate portions of the golf tee that form no part of the claimed design. The broken lines showing a string and holder in FIG. 1.10 are environmental subject matter that form no part of the claimed design.

1 Claim, 10 Drawing Sheets
